WELDER'S MASK

Francis D. Huntsman, Salt Lake City, Utah, assignor to Huntsman Welding Shield Company, Salt Lake City, Utah, a partnership consisting of Francis D. Huntsman, Minnie Huntsman, R. E. Kimberlin, and Marion M. Kimberlin

Application March 29, 1943, Serial No. 480,979.

1 Claim. (Cl. 2—8)

This invention relates to masks for welders and the like, and its general object is to provide an attachment for the mask, that is designed and associated with the headbands thereof for disposal in close proximity to the eyes of the wearer to protect the same from fumes, dirt and other foreign matter, the eye protector including a detachable transparent shield movable into and out of eye protecting position, but casual movement or displacement from either position is practically impossible and the protector in no way interferes with the use of the mask or the movement thereof relative to its headbands.

A further object is to provide an eye protecting attachment for welder's masks, that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a side view illustrating a mask including my eye protector, applied to a wearer, and with the mask and protector in use in full lines and out of use in dotted lines.

Figure 2 is a front view partially in section and with the shield member of the eye protector removed from its attaching band.

Figure 3 is a detail sectional view taken vertically through the shield member and its attaching band, separated from each other, and illustrates the fastening stud for the shield member in elevation.

Figure 4 is a fragmentary side elevation, with the pivot bolt for the mask and shield member attaching band in section.

Figure 5 is a horizontal sectional view taken approximately on line 5—5 of Figure 1.

Referring to the drawing, the mask 1 is provided with the usual head encircling band 2 having longitudinal and transverse supporting straps 3 and 4 respectively. The strap 4 is formed from suitable resilient material and has its end portions bent upwardly to provide U-shaped loops 5 having registering openings therein. Pivot members 6 are disposed in the openings of the loops 5, and the mask is pivoted thereon for swinging movement into and out of use, as shown in full and dotted lines in Figure 1. The outer portions

of the loops 5 bear against the mask for holding the latter in its respective positions. The pivot members extend through the band 2 for securing the strap 4 thereto upon diametrically opposite sides thereof, and the strap 3 has its ends fixed to the headband 2 and its medial portion connected to the strap 4.

The mask 1 is of the usual sheet metal construction and includes a rounded body portion 10 to cover the face and sides of the head, and an upper portion 11 to cover the forward portion of the head. The usual elongated opening is provided in the front of the body portion and the opening is closed by a transparent panel 8 that is held in place by a frame 9.

My eye protector includes a substantially semi-circular or arcuate attaching band that is made up of a strip 10 of metal, having its ends pivotally secured on the bolts 6 between the inner portions 20 of the U-shaped loops 5 and the head encircling band 2, to frictionally hold the eye protector into and out of use, as shown in full and dotted lines in Figure 1. The strip or member 10 is of relatively thin spring material. It has, on its inside, near each of its pivotal points, a projection 11. These projections have inclined or rounded surfaces afforded by making the projections of approximately conical or somewhat dome shape. They may be formed by indenting the strip material from the opposite side.

Toward the front and beyond the projections 11, the strip 10 is bent outwardly as at 12 to provide an arcuate portion 13 to be spaced a considerable distance forwardly of the band 2, as likewise shown in Figure 5, and fixed to the front face of the arcuate portion 13 by rivets 14 is a strip 15 of fiber or the like. The strip 15 is of a length coextensive with that of the arcuate portion 13 and secured to and extending through the strips 10 and 15 midway the ends thereof for disposal at the front of the attaching band is a stud 16 having a reduced outer end. A pair of stud type snap fastener members 17 are likewise secured to the strips 10 and 15 for disposal 45 upon the opposite sides of the stud 16, as best shown in Figure 2.

The shield member includes a panel 18 of transparent material that is mounted in a frame 19, that includes a straight flat upper member 20 having an eyelet 21 centrally arranged therein for receiving the stud 16, and the upper member 20 adjacent its ends has secured thereto socket type fastener members 22 for receiving the stud members 17. By that construction, it will be obvious that the shield member is detachably se-

cured to the attaching band, and such is clearly indicated in Figure 2. The lower portion of the shield member is rounded and centrally recessed as at 23 to provide a nose receiving space, so that the shield member can be disposed substantially in engagement with the face and therefore amply protect the eyes of the wearer.

When the mask is in protective position in front of the user's face, the eyeshield usually is in the upper position and out of the line of sight. The projections 11, by contact with the upper edge of the carrying member 10 or headband 2, hold the eyeshield in that position. When the mask is swung, or about to be swung, upwardly from in front of the face, the member 10 may be swung downwardly to bring the eyeshield to position in front of the eyes. During this movement, the projections 11 ride over the edge of the headband and by frictional contact with the front or outer surface thereof keep the eyeshield in protective position. Spring or yielding properties of the member 10 permit this movement. When the eyeshield is returned to the upper position out of the line of sight, the projections 11 move off the outer surface of the headband and resume contact with the upper edge thereof to retain the eyeshield in upper position. The projections 11 are shown in Fig. 1 adjacent to the upper edge of the headband and about to engage that edge upon slight further upward movement of the eye shield.

As movement of the eyeshield is not affected at

all by the position of the mask, it also may be moved to protective position when the mask is down in front of the face. In some circumstances this is desirable; as, for example, when the eyeshield is of colored material and a welder is not afforded sufficient glare protection from a welding flame by the colored glass of the mask.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

In a face protective device including a headband, an arcuate member of yieldable sheet material pivotally associated near its ends with said headband at its sides and swingable downwardly to and upwardly from position in front thereof, an eyeshield mounted on and depending from the front of said member, and an inclined surfaced projection on the inside of said member near one of its pivotal points contactable with the upper edge of said headband to hold up said member and movable over the edge of said headband to frictionally contact with the surface thereof on downward movement of said member.
